[57] CLAIM

The ornamental design for a damper for springer fork for
motorcycles, as shown and described.

DESCRIPTION

FIG. 1 is a side view of a damper for springer fork for
motorcycles embodying my new design all other sides are
mirror images of that side shown;

FIG. 2 is a top plan view thereof; and,

FIG. 3 is a bottom plan view thereof all other sides are
mirror images of that side shown.
